UNITED STATES PATENT OFFICE.

GERMAIN BRUNNINGHAUSEN, OF PARIS, FRANCE.

DESIGN FOR A PIANO-CASE.

SPECIFICATION forming part of Design No. 36,599, dated October 20, 1903.

Application filed September 3, 1903. Serial No. 171,832. Term of patent 7 years.

To all whom it may concern:

Be it known that I, GERMAIN BRUNNINGHAUSEN, a citizen of the Republic of France, residing at Paris, in the Republic of France, 5 have invented a new, original, and ornamental Design for a Piano-Case, of which the following is a specification, reference being had to the accompanying drawing, forming part thereof.

10 The figure is a perspective view of a piano-case, showing my new design.

What I claim as new, and desire to secure by Letters Patent, is—

The ornamental design for a piano-case as herein shown.

In testimony whereof I have signed my name to this specification in the presence of two subscribing witnesses.

GERMAIN BRUNNINGHAUSEN.
